UNITED STATES PATENT OFFICE.

PETER C. CANIZARO, OF VICKSBURG, MISSISSIPPI.

SHOE-TONGUE DEVICE.

Application filed February 21, 1924. Serial No. 694,426.

To all whom it may concern:

Be it known that I, PETER C. CANIZARO, a citizen of the United States, residing at Vicksburg, in the county of Warren and 5 State of Mississippi, have invented certain new and useful Improvements in a Shoe-Tongue Device, of which the following is a specification.

This invention appertains to shoes and the 10 primary object of the present invention is to provide a novel device for effectively holding a shoe tongue in place against slipping laterally downwardly while the shoe is being worn.

15 A further object of the invention is the provision of a flexible loop or loops disposed at predetermined points on a shoe tongue at the longitudinal center thereof for receiving the shoe lace, whereby the tongue is held in 20 correct position, the formation of the loops being such as to render the lacing of the shoe easy and to cause no discomfort to the wearer.

25 A further object of the invention is to provide novel means for holding a shoe tongue in position, which consist in providing woven thread loops for receiving a shoe lace, which extend through the tongue, the loops being hid at the inner face of the tongue by 30 the usual tongue lining.

35 A still further object of the invention is to provide an improved and novel attachment for shoes of the above character, which is durable and efficient in use, one that is simple and easy to manufacture and one which can be placed upon the market and incorporated with shoe tongues at a small cost.

With these and other objects in view, the 40 invention consists in the novel construction, arrangement and formation of parts, as will be hereinafter more specifically described, claimed and illustrated in the accompanying drawings, in which drawings:

45 Figure 1 is a fragmentary front elevation of a shoe upper showing the improved attachment in use with one type of lacing.

Figure 2 is a similar view showing the attachment used with a different type of lacing.

50 Figure 3 is a fragmentary perspective view of a shoe upper showing the improved

device attachd to a shoe tongue, the lacing being omitted, and

Figure 4 is a fragmentary longitudinal section through a shoe tongue showing the 55 improved device incorporated therewith.

Referring to the drawings in detail, wherein similar reference characters designate corresponding parts throughout the several views, the letter A generally indicates a shoe upper provided with the usual shoe lace opening or eyelet 5 for receiving a 60 shoe lace 6. The tongue 7 of the shoe is of the usual construction and is adapted to engage the inner face of the upper. 65

In the wearing of shoes considerable discomfort is caused the wearer by the shifting of the tongue laterally or downwardly, and while attempts have been made to overcome this tendency, such attempts have all resulted in failure in view of the fact that the 70 means utilized causes discomfort to the wearer in some instance and will not stand up in use in other instances.

In accordance with my invention I provide woven flexible loops 8 which are passed directly through openings 9 in the tongue 7 preferably disposed at the longitudinal center of the tongue. The rear face of the tongue can then be covered with the usual 80 lining which serves as additional means for holding the flexible loop in place. While in the drawings I have shown a pair of loops 8 arranged adjacent to the upper end of the tongue, it is to be understood that only one loop can be used if so desired or two or more loops used and one positioned at the top of the tongue and the other at a 85 point intermediate the ends of the tongue.

While the loop 8 can be formed in 90 different ways, I prefer to construct the same out of a plurality of strands of thread and then unite the different strands by button-hole stitching or the like.

By referring to Figures 1 and 2, it can be 95 seen that the attachment can be used respectively irrespective of how the shoe is laced.

From the foregoing description, it can be seen that I have provided an exceptionally 100 simple and durable attachment for shoes which will cause no discomfort to the wearer

and which will effectively hold a shoe tongue thereof extending through openings formed in a raised position against lateral shifting in the tongue and projecting outwardly from the outer face of said tongue.

Changes in details may be made without In testimony whereof I affix my signature departing from the spirit or the scope of in presence of two witnesses this invention.

What I claim as new is:

The combination with a shoe tongue of a pair of woven loops arranged at the longitudinal center of the tongue at the upper end

PETER C. CANIZARO.
